UNITED STATES PATENT OFFICE.

OTIS A. MYGATT, OF NEW YORK, N. Y.

DESIGN FOR A REFLECTOR FOR ARTIFICIAL LIGHTS.

SPECIFICATION forming part of Design No. 36,214, dated February 3, 1903.

Application filed June 3, 1901. Serial No. 63,043. Term of patent 7 years.

To all whom it may concern:

Be it known that I, OTIS A. MYGATT, residing at New York, in the county of New York and State of New York, have invented and produced a certain new, original, and ornamental Design for a Reflector for Artificial Lights, of which the following is a specification, reference being had therein to the accompanying drawings.

10 The design consists in the form or configuration and the surface ornamentation of a reflector for artificial lights.

Figure 1 is a side elevation of a reflector for artificial lights embodying this invention. Fig. 2 is a broken vertical section of the same.

15 The reflector is composed of transparent glass. The main body A of the reflector is in form of the frustum of a hollow cone. The outer surface of this frusto-conical body is covered with four-sided prisms C, these prisms being of low elevation, the bases of the prisms being in contact. A straight line from the

base to the summit of the frustum would touch the summits of all the prisms in one row or range, so a straight line would touch the bases of all of two proximate rows or ranges of prisms. As such lines would radiate from a common center, (if produced,) it follows that these four-sided prisms are not 25 of equal size and the bases are not true squares; but the prisms diminish in size from the base of the cone as they approach the apex. Above the frusto-conical body A there is a smooth ring B. The inside of the frusto- 30 conical body is smooth, as at D, Fig. 2.

What I claim is—

20 The ornamental design for a reflector for artificial lights, substantially as shown and described.

In testimony whereof I affix my signature in presence of two witnesses.

40 OTIS A. MYGATT.
